UNITED STATES PATENT OFFICE.

JOHN NORMAN GROOVER, OF BIRMINGHAM, ALABAMA.

PICK.

1,357,451.

Specification of Letters Patent.

Patented Nov. 2, 1920.

Application filed May 7, 1919. Serial No. 295,317.

To all whom it may concern:

Be it known that I, JOHN N. GROOVER, a citizen of the United States, residing at Birmingham, in the county of Jefferson and State of Alabama, have invented a new and useful Pick, of which the following is a specification.

This invention relates to improvements in tools of the character known as picks, the object of the invention being to provide an improved tool wherein the points can be renewed or differently shaped points substituted for those originally furnished with the tool.

A further object of the invention is to provide a body or head adapted to interchangeably carry a plurality of different implements and in which the use of screws for holding the implement in place is entirely eliminated.

A further object of the invention is the provision of a tool of the character set forth which is comparatively simple in construction, inexpensive to manufacture and very durable in use.

With the foregoing and other objects in view, which will appear as the description proceeds, the invention consists in the novel features of construction and combination of parts which will be more fully described hereinafter and particularly pointed out in the claims.

In the drawings accompanying and forming part of this specification,

Figure 1 is a side elevation, partly in section, of my improved pick, showing a portion of a handle attached thereto;

Fig. 2 is an end elevation, broken away at its lower end;

Fig. 3 is a cross section taken on the line 3—3 of Fig. 1; and

Fig. 4 is an enlarged detail perspective view of one end of an implement adapted for use in my improved construction.

The same characters of reference designate the same parts in the different figures of the drawings.

As is well known, the ordinary pick is used until the points thereof are worn off so short that the tool is of no service, whereupon it is thrown away, since the cost of

steel and labor is so high that it is more expensive to buy the steel and hire a blacksmith to re-point the tool than a new one would cost. The object of this invention, therefore, is to provide a pick that is so formed that the working points are detachably secured thereto, so that when a point becomes worn, or it is desired to use a point of different formation, all that is necessary is to remove the discarded point and substitute the one desired.

Referring to the drawings, 2 designates a body or head having the usual opening 3 therein for the reception of the end of a handle 4, the opening and handle being slightly tapered toward the outer end thereof to prevent separation of the head from the handle when in use. The head 2 shown herein comprises a pair of oppositely extending arms 5, the ends of which are sawed off square. Each of these arms is provided with a longitudinally extending opening 6 communicating at its extreme inner end with a small laterally extending recess 7. Within the opening 3 at the outer end thereof is formed in each of the arms 5 a recess 8, which communicates through a channel 9 with the opening 6 in the arm.

An implement 10 having any suitable form of point is provided with a stem 11, the size of which immediately adjacent to its point of juncture with the implement is such as to snugly fit the outer end of the opening 6 and tapered down on one side thereof to a smaller size at its end, as clearly shown in Figs. 1 and 4. The end of the implement on which the stem 11 is formed is of approximately the same size as the sawed off ends of the arms 5, whereby the implement is provided with a shoulder 12 surrounding the stem. The stem 11 is provided at its end, on the side opposite the tapered side with a laterally projecting lug 13 adapted to seat within the recess 7 of the arm 5. For securing the stem in the opening 6 with its lug in engagement with the recess 7, I provide a wedge-shaped member 14 adapted to pass through the channel 9 and form a wedge between the tapered side of the stem 10 and one of the side walls of the opening 6, the wedge 14 having a laterally extending

head or lug 15 adapted to seat in the recess 8 within the opening 6 of the body.

In assembling the tool, the stem 11 is inserted in the opening 6 by tilting the implement so that the tapered side of the stem rests against the side of the opening opposite the side having the recess 7, and the stem slid in until its lug 13 reaches the recess 7, whereupon the implement is tilted in the opposite direction so as to cause said lug to seat within the recess. The shoulder 12 of the implement is thus firmly seated on the end of the arm 5, whereupon the wedge 14 is inserted from the end of the handle-opening 3 through the communicating channel 9 and pushed down until its lug 15 is seated within the recess 8 of the head. The handle is then inserted through the opening 3, and owing to the tapered formation of the opening 3 and of the handle the sides of the handle will lie against the ends of the wedges 14 and hold them firmly seated in the arms, whereby the implement is positively locked against withdrawal from the opening 6.

From the foregoing it will be seen that when a job is to be done that requires the use of a number of implements having differently formed cutting ends, such as picks, mattocks, axes and the like, it is necessary to have only one head, and all of the implements required having the same formation of stem may be interchangeably secured in said head in the manner above described.

It should also be noted that the recess 8 or slot formed thereby, communicates with the convex side of the head, as distinguished from the inner or concaved side thereof, and that the outer wall of the longitudinally extending opening 6 in each arm, extends in a plane, to clear the convex face at the outer side and at a point diametrically opposite thereto, at the sleeve or body portion 2, thus permitting the wedge keys 14 to be engaged in position or disengaged therefrom, longitudinally, to clear the outer face of the head, thus greatly facilitating the application thereof and the securing of the parts in position.

While I have described in detail the structure herein illustrated, it is to be understood that I do not thereby limit my invention to the precise features of construction shown, as I am aware that many mechanical changes and modifications may be made therein without departing from the spirit and scope of the invention as set forth in the claims appended hereto.

Having thus described my invention, what I claim is:

1. A tool of the class described having a head provided with an arm having a longitudinally extending opening forming an end wall, said opening being provided with a recess at one side adjacent its inner end

and provided with a communicating slot having an opening extending laterally through the head, a stem adapted to be secured to said head and provided with a lug projecting laterally therefrom at its inner end to enter said recess from the opposite side of the opening and an elongated wedge key adapted to engage the slot through the opening thereof in a plane clear of the outer end of the head and into the space between the stem and the wall of the longitudinal opening to hold the lug in the recess, said stem having an implement formed therewith to produce a shoulder at the juncture thereof to engage and conform to said end wall.

2. A tool of the class described comprising a head having a pair of arms projecting therefrom, the outer face being convex and the inner face concave, each of said arms being provided with a longitudinal opening forming an end wall at the free end of each arm and having a recess in one side thereof at its inner end, said openings each communicating with the outer face of the head through a slot therein, said recess being disposed opposite the slot of each opening, an implement for each arm having a reduced portion forming a shoulder adapted to engage the outer end of each arm and conform thereto, said reduced portion being tapered to provide a stem having a lateral projection at one side adapted to engage said recess and leave a space of tapered formation between its opposite side and the adjacent wall of the opening, and a wedge key engaged through the slot of each recess and in said space throughout the length of the arms and stems and adapted to be engaged in position longitudinally or disengaged in a plane clear of the convex face of the head.

3. A tool of the class described comprising a head provided with an opening for the reception of a handle and having a pair of arms projecting therefrom, each of said arms being provided with a longitudinal opening, the outer wall of each of which extends in a plane to clear the outer face of the head at the diametrically opposite side or point and a laterally extending recess communicating with said opening at its inner end, the front of the head having a right angularly formed slot communicating with said opening first-named and with the front surface of the head at the convex side thereof, an implement conforming in cross section to each arm and provided with a tapered stem projecting therefrom forming a shoulder adapted to engage the ends of the arms around the longitudinal openings therein, said stems being beveled at one side and having a lug projecting from the opposite side adapted to enter a lateral recess by angular engagement of the

stems in the openings of the arms, and a wedge shaped member adapted to engage in said longitudinal openings between the stems and opposite walls in and through 5 said right angularly formed slot whereby a handle disposed in the opening of the head will retain the same in position.

In testimony that I claim the foregoing as my own, I have hereto affixed my signature in the presence of two witnesses.

JOHN NORMAN GROOVER.
